UNITED STATES PATENT OFFICE.

THOMAS E. BROWN, OF NEW YORK, N. Y., ASSIGNOR TO OTIS ELEVATOR COMPANY, OF JERSEY CITY, NEW JERSEY, A CORPORATION OF NEW JERSEY.

FURNACE-BELL HOIST.

1,127,351.

Specification of Letters Patent. Patented Feb. 2, 1915.

Application filed December 4, 1912. Serial No. 734,803.

To all whom it may concern:

Be it known that I, THOMAS E. BROWN, a citizen of the United States, residing in New York, in the county of New York and 5 State of New York, have invented a new and useful Improvement in Furnace-Bell Hoists, of which the following is a specification.

My invention relates to bell hoisting mechanism for use in connection with blast furnaces.

An object of the invention is to provide improved means for operating the bells which seal the furnace.

15 Other objects of the invention and the exact nature thereof will appear hereinafter.

Referring to the accompanying drawings which illustrate an embodiment of my invention, Figure 1 is a part sectional elevation view of a furnace with the invention applied thereto; Fig. 2 is a detail view on a larger scale of my improved means for multiplying power which is transmitted to hold the bells in sealed or closed position; 25 Fig. 3 is a detail sectional view showing a stop device.

As shown in Fig. 1 a blast furnace A comprises a compartment 1 to receive a charge of coke, limestone, or ore, etc. The bottom 30 of this compartment is closed by a large bell 2. At the upper end of the compartment 1 is a receptacle or hopper 4 which extends into said compartment and has its lower end closed by a small bell 3. The bell 2 is connected through a rod 5 to a walking beam or lever 6, connected, by a pivot 7, to the overhead frame work. The small bell 3 is connected to a hollow rod or tube 8 pivoted at its upper end to a walking beam 6.

40 The rod 5 extends through the tube 8. The charge for the furnace is hoisted from the pit 9 in skips 10 which travel along the inclined tracks 11. Hoisting ropes or cables 12 are connected to the skips and extend over 45 a direction sheave 13 and from thence to the hoisting mechanism H. The parts thus far described may be of usual or well known construction.

The hoisting mechanism for operating 50 the bell 3 comprises a small electric motor 14, connected through worm gearing or other speed reduction mechanism to a shaft 15 (Fig. 2) to which is secured a pinion 16. An annular gear 17 in mesh with the pinion 16 is secured to a crank shaft 18, to which is

also fixed a crank 19. A connecting rod 20 extends from the crank to a lever 21 having a pivot 22 which connects the lever with the outer end of the walking beam 6. A counterweight 23, which, as shown in Fig. 1, is 60 made in sections for the purpose of adjustment, is connected through the chain 24 to the outer end of the lever 21. Said chain runs on a guide sheave 25. An adjustable stop device is located directly over the connecting rod 20, and comprises a U-shaped piece 26 secured between the parallel members of the lever 6. The head of a bolt 27, which extends through the piece 26, is located directly over the upper end of the connecting rod 20, in position to be engaged thereby, as will presently be described. Washers 28 form a convenient means of adjusting the position of the stop 27.

In operation, when a skip 10 has discharged its load of coke, or ore, or other material, into the hopper 4, the bell hoisting motor 14 is started and operates to impart one complete rotation to the annular gear 17. The current is then automatically cut off and 75 an electric brake 29 is applied to bring the mechanism to rest with the parts in the position shown in the drawings. When the crank 19 commences its rotation the rod 20 is carried up into engagement with the stop 80 27. The levers 21 and 6 then maintain a fixed relative position and operate as a unit until the crank 19 has nearly completed its rotation. As the outer end of the lever 6 moves upward, the bell 3 is lowered and permits the material in the hopper to fall into the compartment 1. As the rod 20 is carried downward the bell 3 is again lifted to its closing position, which is reached shortly 85 before the crank 19 has completed its rotation. The lever 21 is then rotated about its pivot through a small angle, thereby separating the connecting rod from the stop 27. If the lever 21 is pivoted at its center the 90 downward pull on the rod 20 will be equal to the weight 23, but the downward pressure at the pivot 22 will be double this amount. In other words, by the use of the lever 21 and weight 23, the downward pull at the 95 outer end of the lever 6 is double that of the usual arrangement in which the connecting rod is pivoted directly to the walking beam. The upward pressure applied through the walking beam to the bell 3 is correspondingly increased. This is an important fea- 100 105 110

ture of the invention, as the power applied through the walking beam must be sufficient not only to hold the combined weight of the bell and the charge supported thereby, but the bell must be sealed gas tight against the top rim of the furnace. It will be seen that with the system of leverage employed the torque of the motor need not be more than half that required to operate the usual mechanism. It will also be observed that the weight 23 acts as a partial counterbalance weight for the charging material, so that the duty required of the motor is materially lessened during the intermediate portion of its operation. The lever 21 of course need not be pivoted at the center, as the pivot point may be shifted in either direction, resulting in a corresponding variation in the leverage obtained. Another advantage of the present arrangement is that the bell is always held closed with full power while the motor is at rest and does not require the accuracy of adjustment that is required when the connecting rod 20 is pivoted directly to the walking beam. In the latter case any wear of the parts, looseness in the bearings, etc., will tend to relieve the pressure on the bell. This is not true, however, of the present invention, where the power is transmitted through the lever 21, as any variation in the adjustment or wear of parts, etc., will operate merely to slightly vary the angle of the lever 21, without in any way affecting the pressure applied to the bell.

I wish not to be limited to the precise construction herein shown, as various modifications might be made by those skilled in the art, without departing from the spirit and scope of the invention.

What I claim as new and desire to secure by Letters Patent of the United States is:—

1. In a furnace, the combination of a bell, a walking-beam, a connecting rod between the bell and one end of the walking beam, a lever pivoted to the other end of the beam, hoisting mechanism, a connecting rod, between said mechanism and one end of the said lever, a weight supported from the other end of said lever, and a stop to limit the movement of the said lever about its fulcrum.
2. In a furnace, the combination of a bell, a walking beam, means to connect said parts, a lever pivoted to the walking beam, an adjustable stop in position to limit the relative movement of the lever and walking-beam, and a hoisting device and counter-weight connected to the lever.
3. In a furnace, the combination of a closure, a walking-beam connected thereto and operable to move the said closure into and out of closed position, a lever pivoted to the walking beam, an adjustable stop carried by the beam, operating mechanism connected to the lever, and means to hold the

lever against said stop during the movement of the closure and permitting independent movement of the lever when the closure is in closed position.

4. In a furnace, the combination of a bell 70 forming a closure for the furnace, a walking-beam, a rod connecting one end of the walking-beam to the bell, a lever pivoted to the opposite end of the walking-beam, a stop carried by the walking beam, a crank 75 shaft, a crank, a connecting rod connected to the crank and one end of the lever, a weight connected to the opposite end of the lever sufficient to hold the lever against the stop during the movement of the bell, the 80 parts being so adjusted that the bell will be brought to closed position and the lever moved out of contact with the stop as the crank nears a dead center position, and means to rotate the crank shaft.

5. A blast furnace hoist comprising a charging bucket, means for hoisting said bucket, a bell, a closure for said bell, means to lift and lower said closure into and out of closed position, and means independent 90 of said hoisting means for multiplying the pressure with which said closure is held in closed position.

6. A blast furnace hoist, comprising a charging bucket, means for hoisting said 95 bucket, a bell, a closure for said bell, means to lift and lower said closure into and out of closed position, and means independent of said hoisting means for automatically applying a holding pressure to the closure 100 after it reaches a closed position.

7. A blast furnace hoist comprising a charging bucket, means for hoisting said bucket, a furnace bell, motor mechanism associated with said bell for operating it to 105 and from a closed position, and means independent of the said hoisting means and associated with said motor mechanism for permitting a continued operation of the motor mechanism after the bell has reached a 110 closed position.

8. A blast furnace hoist comprising a charging bucket, means for hoisting the bucket, a closure for the furnace, means for operating said closure independent of said 115 hoist means, and a compound leverage system forming an operating connection between said mechanism and the closure.

9. A blast furnace hoist comprising a charging bucket, hoisting mechanism therefor, a furnace bell, a walking beam connected thereto, a counterweight pivoted to said walking beam and adapted to maintain the bell in closed position with a predetermined pressure, and means independent of said 125 hoisting mechanism for varying said pressure.

10. A blast furnace hoist comprising a charging bucket, hoisting mechanism therefor, a furnace bell, a walking beam connect- 130

to said bell, a lever pivoted to said beam, a weight on one end of the lever, and means connected to the other end of said lever adapted to effect the operation of said bell independently of the said bucket hoisting mechanism.

In testimony whereof, I have signed my
